NECKTIE RACK

John H. Doak, Walla Walla, Wash.

Application August 30, 1954, Serial No. 32,067

Term of patent 14 years

(Cl. D33—8)

Fig. 1 is a front elevation of a necktie rack showing my new design.

Fig. 2 is a side view of the same.

Fig. 3 is a top view of the same.

I claim:

The ornamental design for a necktie rack, substantially as shown.
